UNITED STATES PATENT OFFICE.

JAMES LAWRENCE, OF CHICAGO, ILLINOIS.

RESTRAINING DEVICE.

1,236,454.

Specification of Letters Patent. Patented Aug. 14, 1917.

Application filed August 2, 1916. Serial No. 112,882.

To all whom it may concern:

Be it known that I, JAMES LAWRENCE, a citizen of the United States, residing at Chicago, in the county of Cook and State 5 of Illinois, have invented a new and useful Restraining Device, of which the following is a specification.

The object of the invention is to provide a relatively inexpensive restraining jacket 10 adapted for use in connection with violent, irrational or insane patients to prevent them from injuring themselves or others.

Further objects of the invention will appear as the description proceeds, it being 15 understood that changes in the precise embodiment of the invention herein disclosed, can be made within the scope of what is claimed, without departing from the spirit of the invention.

20 In the drawings:—

Figure 1 is a perspective view of the device as seen when applied to a patient.

Fig. 2 is a similar view of the apparatus, unattached.

25 The jacket consists of a front or chest member 10 connected by shoulder members 11 with overlapping back members 12 and 13 provided at the neck portion 14 and at intermediate points with eyelets 15 for engagement by a lacing member 16. The front member 10 is connected to an intermediate point of a waist or belt member 17, and the back members 12 and 13 are also connected with said waist or belt member 30 at intermediate points thereof or set back from the extremities of the same, so that when the back members are in their proper relative positions, at the adjustment 35 adapted to suit the patient, the belt or waist member extensions 18 extend beyond said back members and by means of eyelets 19 and 20 may be secured through the agency of the above mentioned lace 16, or by a a separate lacing if preferred.

40 Firmly attached terminally to the waist or belt member at the sides thereof are anchor straps 21 and 22 which in common with the jacket may be of any suitable or preferred material having the requisite 45 strength, one of said anchoring straps being provided with a running loop or eye 50 23 through which the other strap is extended as shown in Fig. 2.

55 After the jacket has been suitably and effectually laced upon the patient, the anchoring straps are wrapped around or other-

wise firmly engaged with the side bars or rails of the bedstead, and then the straps are engaged by passing one of them through the loop 23 of the other, the lacing 16 also 60 being passed through said running loop, and the free ends of said inserted strap and lacing are permanently tied to a bed post or other fixed portion of the bedstead as at 24 in Fig. 1.

65 It will be observed that there are no knots, ties or loose ends within reach of the patient and it is impossible for the latter to leave the bed or to reach the point of attachment of the fastening means at 24, although 70 the patient is free to rise to a sitting position.

75 Moreover, the device described allows the patient free use of his arms and feet and hence does not subject him to the inconvenience or unnecessary restraint incident to the use of straps, as ordinarily applied, straight jackets and the like.

80 It will be understood that any suitable material may be employed in the construction of the device, such as leather, linen, ducking, canvas, etc., or any combination thereof and the members of the jacket, though relatively restricted in area may for purposes of ventilation be perforated without detracting from the efficiency of the apparatus. It will also be observed that by 85 means of the lacing and the plurality of eyelets, the neck and waist portions of the jacket may be adjusted to any necessary extent and independently of each other, to suit the proportions of the patient, and either continuous or separate lacings may be used in this connection, the former, however, being preferable for the reason that it facilitates the securing of the extremity thereof 90 with the anchor strap as explained.

95 What is claimed is:—

1. A restraining device comprising a belt having its ends overlapped at the back, and 100 being provided at the front with a chest member extended in a single length to a point adjacent the chin of the wearer, the chest member being bifurcated at its upper end to form a neck-receiving opening, and 105 to define a pair of back strips disposed in alinement, one behind the other, the back strips being connected with the ends of the belt in spaced relation to the extremities thereof, the back strips on the one hand, 110 and the body portion of the belt and the ends of the belt on the other hand, being provided

with eyelets; and a lacing means engaged with the eyelets.

2. In a structure of the class described, a body-engaging restraining device comprising separable parts and a lacing cord attached at one end to one of said parts and forming a connection uniting said parts; and oppositely extended flexible elements having their inner ends attached to the restraining device, the outer end of one flexible element having a loop, and the outer end of the other flexible element being extended slidably through the loop to form a support-engaging noose, the other end of 15 the lacing cord being extended slidably

through the loop, the outer end of said other flexible element and said other end of the lacing cord being prolonged to a point remote from the restraining device to form support-engaging tying terminals preventing an expansion of the noose and a loosening of the lacing cord in the restraining device. 20

In testimony that I claim the foregoing as my own, I have hereto affixed my signature in the presence of two witnesses. 25

JAMES LAWRENCE.
